UNITED STATES PATENT OFFICE

ARTHUR J. MUCHNICK, OF ELIZABETH, NEW JERSEY, ASSIGNOR OF ONE-HALF TO
BENJAMIN EPSTEIN, OF BROOKLYN, NEW YORK

DESIGN FOR A CLOCK DISPLAY ADVERTISING UNIT

Application filed March 25, 1932. Serial No. 43,289. Term of patent 3½ years.

To all whom it may concern:

Be it known that I, ARTHUR J. MUCHNICK, a citizen of the United States, residing at Elizabeth, in the county of Union and State of New Jersey, have invented a new, original, and ornamental Design for a Clock Display Advertising Unit, of which the following is a specification, reference being had to the accompanying drawing, forming part thereof.

Fig. 1 is a plan view of a clock display advertising unit showing my new design, and

Fig. 2 is a section showing my method of employing a celluloid border.

The provision of a suitable lighting system within the clock will not only illuminate the

portion devoted to the display of changeable advertisements, but will also light up the celluloid border. The celluloid or similar substance may be highly colored, so that upon illumination, it will present an appearance approximating that of a neon tube. The clock face may be of dark color, in order to accentuate the striking luminosity of the border.

What I claim is:

The ornamental design for a clock display advertising unit, as shown and described.

In testimony whereof I affix my signature.

ARTHUR J. MUCHNICK.
